UNITED STATES PATENT OFFICE.

OLGA B. HAWES, OF PATERSON, NEW JERSEY,

SYRINGE AND TUBE HANGER.

1,225,243.

Specification of Letters Patent.

Patented May 8, 1917.

Application filed August 3, 1916. Serial No. 112,981.

To all whom it may concern:

Be it known that I, OLGA B. HAWES, a citizen of the United States, residing at Paterson, in the county of Passaic and State 5 of New Jersey, have invented a new and useful Syringe and Tube Hanger, of which the following is a specification.

This invention relates to hangers particularly designed for use in connection with 10 fountain syringes, one of the objects of the invention being to provide a simple, compact and efficient device of this character which will not only act as a support for a fountain syringe but will also serve as a 15 means for holding the tube so that it will drain readily and will not become crinkled or folded.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

30 In said drawings:—

Figure 1 is a rear elevation of the hanger. Fig. 2 is a plan view thereof.

Fig. 3 is a section on line 3—3, Fig. 1.

Referring to the figures by characters of 35 reference 1 designates a depending hook formed by one end portion of a wire 2 the other end portion of which is bent to form a support engaging eye 3. Another wire has its end portions twisted about and with the 40 wire 2 as indicated at 4, this second wire 5 being shaped to provide an elongated arcuate frame 6 which extends laterally and downwardly in opposite directions from the wire 2 and has its end bent to constitute 45 downwardly converging depending loops 7.

At desired intervals the sides of the frame 6 are connected by arcuate cross strips 8, these cross strips and the depending loops 7 co-operating to form a rack for supporting one or more convolutions of tubing.

50

In using the device, the bag or container of the fountain syringe is suspended from the hook 1, after which the entire structure can be connected to a suitable support extending through the eye 3. The tube of the 55 fountain syringe can then be looped over the rack made up of the frame 6 and the cross strips 8 and obviously these loops will thus be held smoothly and without abrupt bends which tend to injure the tube.

60

It is to be understood that if desired the hanger can be made of some material other than metal wire. For example, strands of celluloid or the like may be employed.

What is claimed is:—

65

1. A hanger including an arcuate frame, arcuate cross strips connecting the sides of the frame and co-operating therewith to form a tube supporting rack, a hook depending from the middle portion of the frame, and 70 a support engaging element extending upwardly from the middle portion of the frame.

2. A hanger including an arcuate frame formed of wire and having its ends constituting depending loops, arcuate cross strips connecting the sides of the frame and co-operating therewith to form a tube supporting rack, a wire depending from the frame at the center thereof and forming a receptacle supporting hook, and a support engaging element extending upwardly from the center of the frame.

75

In testimony that I claim the foregoing as my own, I have hereto affixed my signature 80 in the presence of two witnesses.

OLGA B. HAWES.

Witnesses:

ELLA C. GRISWOLD,
VIOLET L. HEINSON.
